UNITED STATES PATENT OFFICE.

THOMAS W. BRYANT, OF TORRINGTON, CONNECTICUT.

DESIGN FOR A DOG-COLLAR.

SPECIFICATION forming part of Design No. 21,344, dated February 16, 1892.

Application filed December 21, 1891. Serial No. 415,798. Term of patent 3½ years.

To all whom it may concern:

Be it known that I, THOMAS W. BRYANT, a citizen of the United States, residing at Torrington, in the county of Litchfield and State 5 of Connecticut, have invented a certain new and original Design for Dog-Collars, of which the following is a full, clear, and exact specification.

Reference is to be had to the accompanying 10 drawing and the numerals marked thereon, forming a part hereof.

The essential features of my design for a dog-collar comprise the low pyramidal facets provided with links, the projecting ends of 15 which are diamond-shaped, as shown.

The collar consists of a series of rectangular links 1 of slightly greater length than breadth and having their outer faces of low pyramidal form, as shown at 2. The ends of

these links are but slightly separated, as appears in the drawing. Alternating with these links are connecting-links 3, whose ends project at either side beyond the lines formed by the sides of the links 1. The ends of said links 3, as shown, are obtusely angular, the apex of the angle lying in the line of the joint between two adjacent links 1, and the spaces between the links 3 lying in line, as seen at 4, with the centers of the several links 1.

I claim--

The design for dog-collars, substantially as herein shown and described.

In testimony whereof I affix my signature in presence of two witnesses.

THOMAS W. BRYANT.

Witnesses:

HENRY L. PIDGE,
JOHN W. BROOKS.
